Primary Examiner — Randall H Gholson*(74) Attorney, Agent, or Firm* — Ryan Kromholz & Manion, S.C.(57) **CLAIM**

The ornamental design for a reloader, as shown and described.

DESCRIPTION

FIG. 1 is a top perspective view of an embodiment of the reloader;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a top perspective view of another embodiment of the reloader;

FIG. 7 is a bottom perspective view thereof;

FIG. 8 is a top plan view thereof;

FIG. 9 is a bottom plan view thereof; and,

FIG. 10 is a left side elevation view thereof.

The broken lines in the drawings represent unclaimed subject matter and form no part of the claim.

1 Claim, 4 Drawing Sheets(56)
